(57) **CLAIM**

The ornamental design for a rotary cutting head, as shown and described.

DESCRIPTION

FIG. 1 is a perspective view of a rotary cutting head showing my new design;

FIG. 2 is a top plan view of the rotary cutting head of FIG. 1;

FIG. 3 is an end elevational view of the rotary cutting head of my new design;

FIG. 4 is a side elevational view of the rotary cutting head of FIG. 3, the opposite side being a mirror image of the side shown;

FIG. 5 is a rear elevational view of a rotary cutting head showing my new design; and,

FIG. 6 is a bottom plan view of a rotary cutting head showing my new design.
